UNITED STATES PATENT OFFICE.

GEORGE WARREN PAYNE, OF LITTLE NECK, NEW YORK.

ROAD-CART.

SPECIFICATION forming part of Letters Patent No. 357,501, dated February 8, 1887.

Application filed November 23, 1886. Serial No. 219,662. (No model.)

To all whom it may concern:

Be it known that I, GEORGE WARREN PAYNE, a citizen of the United States, residing at Little Neck, in the county of Queens and State of New York, have invented a new and useful Improvement in Road-Carts, of which the following is a specification.

My invention relates to improvements in road-carts; and it consists of the peculiar combination of devices and novel construction and arrangement of the various parts for service, substantially as hereinafter fully described, and particularly pointed out in the claims.

Heretofore it has been proposed to provide a road-cart or two-wheeled vehicle with a transverse spring-bar which is affixed to the lower side of the body, and to pivotally connect the rear ends of the thills to the said spring-bar and to the body at an intermediate point of their length, so as to obviate the objectionable jarring motion of the thills from becoming communicated to the body.

I am also aware that it has been proposed to provide an intermediate coupling-bar between the rear of the thills and the spring-bar, so that the elevation of the rear ends of the thills can be varied to cause the body to assume a horizontal position; but the method of coupling the said intermediate bar to the spring is objectionable, because of the fact that the spring-bar is liable to be twisted to a greater or less degree by the vibrating motion of the thills on the coupling-bar, which consequently unduly strains and weakens the spring-bar. In my improved road-cart I propose to provide this intermediate coupling-bar, which is to be pivotally connected at its lower end to the transverse spring or spring-bar so as to move or swing at right angles to the vertical plane of movement of the said spring, and thereby prevent the coupling-bar from twisting the spring, all as will be more fully described and claimed.

In the drawings hereto annexed, which illustrate a road-cart or two-wheeled vehicle embodying my improvements, Figure 1 is a side elevation. Fig. 2 is a bottom plan view. Fig. 3 is a detached perspective view of the intermediate coupling bar or rod and a portion of the spring and thill-iron which is connected thereto. Fig. 4 is a detail view of the couplings for the thills to the body.

Referring to the drawings, in which like letters of reference denote corresponding parts in all the figures, A designates the axle of my improved road-cart or two-wheeled vehicle; B, the carrying-wheels, which are fitted upon the extremities of the axle in the usual manner. The body C of the vehicle or cart is provided in its sides, at or near the middle thereof, with transverse aligned slots c, through which the axle A passes, and between the body and the axle are interposed springs D, which are suitably secured to the body at the sides thereof and to the axle, so as to cushion the body and give an easy and resilient motion thereto. The body is free to vibrate or move up and down, and the axle works in the slots in the sides of the body, which are of sufficient size to permit the body to have the necessary freedom of movement.

E designates a block, which is rigidly affixed to the under side of the body of the vehicle in front of the axle thereof, and to this block is rigidly affixed a transverse spring or spring-bar, F, the bolts or other devices which secure the said spring or spring-bar to the block being passed through the middle of the spring and the block to secure both the spring and block to the body of the cart. The spring is thus arranged beneath and out of contact with the body of the vehicle by which it is carried, and the ends of the spring are thus free to vibrate vertically without coming in contact with the body of the vehicle and without hinderance therefrom. The ends of the spring or spring-bar are extended slightly beyond the vertical sides of the body of the cart or vehicle, and to these extended ends of the spring are connected the lower ends of vertically-disposed coupling-bars G, which are adapted to swing or move in a plane at right angles to the line of movement of the said spring, and with the same, as the coupling-bars are attached thereto. The lower ends of these coupling-bars are each pivotally connected by a transverse pin or bolt to a segmental plate, g, the ends of which are fitted on opposite sides of the ends of the spring, and through the lower terminal ends of the diverging arms of the coupling-plate are formed transverse eyes g', which align with corresponding eyes formed in the outer end of the spring-bar, so that a transverse pivot-bolt, g², can be passed through the said aligned eyes.

10

to pivotally connect the coupling-plate, the bar pivoted thereto, and the spring or spring-bar together, to adapt them to be moved vertically at the same time, and yet permit the coupling-bar to swing in a different direction with the thill-iron and without affecting the proper vertical movement of the spring or spring-bar, thereby relieving the spring of all undue twisting and straining, and very materially increasing the durability thereof.

H designates the thills, which are curved downwardly, as at h, and these curved ends of the thills are extended in rear of the front end of the body of the cart, so that they can be easily connected with the coupling-bars. The thills are connected together and braced at an intermediate portion of their length by means of the usual tie-bar, h', which is secured in the opposing sides of the thills at points where the downwardly curved portions h commence. The thills are pivotally connected with the body of the cart, at the front thereof, by means of intermediate shackles or couplings, I, which are rigidly affixed to the body and the tie-bar of the thills and pivotally connected together, as shown very clearly in Fig. 4 of the drawings. The shackles or couplings are located at the front end of the body, within the sides thereof, and between the said body and the tie-bar connecting the thills.

J designates the thill-irons, which are rigidly affixed to the under side of the thills by means of bolts or like securing devices, and the rear terminal ends of the said thill-irons are enlarged to provide or form the integral heads j, which are bifurcated, as shown, to form the arms j', through which are formed transverse aligned openings that are adapted to coincide with one of a series of openings, g³, formed in the coupling-bar, a pivot-bolt, J', being passed through the aligned openings in the head and the coupling-bar to pivotally connect the thill-iron and the coupling-bar together.

45 This being the construction of my invention, the operation of the same is as follows: When the vehicle is in motion, the thills vibrate up and down, the couplings or shackles serving as the pivots or center of motion of the said thills, the front and rear end of the said thills on opposite sides of the shackles moving vertically under the jogging motion of the draft-animal. As the thill-irons are pivotally connected to the coupling-bars, the latter are swung backward and forward slightly with the said irons, and the lower ends of the coupling-bars being connected with the spring through the intermediate segmental plates, the free ends of the latter are moved vertically with the thill-irons and the coupling-bars. The strain and twist on the spring or spring-bar is relieved by the coupling-bar moving on its pivot back and forth with the

thills; and by reason of this peculiar arrangement of devices the horse-motion, which is objectionable in many vehicles of this class, is entirely overcome, and the spring is relieved from undue twisting, to thereby increase its durability. The side springs cushion the body of the vehicle, to insure an easy and resilient motion thereto, and the horizontality of the body can be readily varied by merely elevating or depressing the point of connection of the thill-irons and the thills with the swinging coupling-bars.

It will thus be seen that I provide an improved road-cart or two-wheeled vehicle of simple and durable construction, in which the horse-motion is entirely overcome, the body is insured an easy-riding motion, and which can be easily adjusted.

I have an application pending, which was filed January 7, 1886, that shows the links connecting the ends of the thills and the spring-bar.

Having thus fully described my invention, what I claim as new, and desire to secure by Letters Patent, is—

1. In a road-cart, the combination of a body, the transverse spring F, connected to the body, the plates g, pivotally connected to the terminal ends of the spring, and the coupling-bar G, having the rear ends of the thills pivotally connected to the same and pivoted at their lower ends to the said plates g, to move vertically with both the spring and thills, and also back and forth with the thills only at right angles to the vertical movement of the spring, substantially as described, for the purpose set forth.

2. In a road-cart, the combination of the body having the transverse aligned slots in its sides, the axle passing through the said slots, the carrying-wheels, the springs interposed between the body and the axle, the fixed block on the under side of the body in front of the axle, the transverse spring arranged in front of the axle and rigidly affixed at its middle to the block, and thereby arranged below and out of contact with the body to insure free vertical movement to the ends, the thills pivotally connected to the body at an intermediate point of their length by the couplings or shackles, and the coupling-bars pivotally connected to the rear ends of the thills and the terminal ends of the transverse spring, substantially as described, for the purpose set forth.

In testimony that I claim the foregoing as my own I have hereto affixed my signature in presence of two witnesses.

GEORGE WARREN PAYNE.
